Mr. Attorney

UNITED STATES PATENT OFFICE.

JOSEPH F. LAMB, OF NEW BRITAIN, CONNECTICUT, ASSIGNEE TO LANDERS, FRARY & CLARK, OF NEW BRITAIN, CONNECTICUT, A CORPORATION OF CONNECTICUT.

RANGE.

Application filed April 2, 1921. Serial No. 453,105.

To all whom it may concern:

Be it known that I, JOSEPH F. LAMB, a citizen of the United States, residing at New Britain, in the county of Hartford, State of Connecticut, have invented certain new and useful improvements in a Range, of which the following is a specification.

The present invention has as its object to provide an electric range having various features of novelty and advantage.

In accordance with the present invention, the frame work of the range, for the most part, is formed of irons angular in transverse section; the cover plates and panels are formed of sheet metal pressed or bent into the desired shape, and the parts are so arranged and assembled that practically all bolts, rivets or other means for securing the parts together are hidden from view; consequently, the range presents a very pleasing and neat appearance and, furthermore, there being no exposed bolt heads, or the like, about which grease or other foreign matter can accumulate, it is very easy to keep the range in a clean and sanitary condition. Since the range is almost entirely made up of light metal parts which may be cheaply and easily assembled, a very economic structure is presented, while at the same time the parts are so arranged and secured together that the range has the necessary rigidity and strength. The invention is also concerned with the novel construction and arrangement of the oven.

In the accompanying drawings:

Fig. 1 is a perspective view of the range constructed in accordance with that embodiment here selected for purpose of illustration.

Fig. 2 is a perspective view of the skeleton or framework of the range.

Fig. 3 is a sectional view showing the manner in which the switches and fuses are enclosed.

Fig. 4 is a sectional view through one end of the body portion of the range and shows the manner in which one of the end panels is assembled on the frame.

Fig. 5 is a top plan view of one of the brackets 13.

Fig. 6 is a horizontal sectional view taken through the back of the range beneath the oven.

Fig. 7 is a vertical sectional view taken

through the back of the range, the oven being omitted.

Fig. 8 is a vertical sectional view taken through the back of the range and the shelf thereon.

Fig. 9 is an enlarged detail view showing the manner in which the hot plates are supported.

Fig. 10 is a sectional view taken vertically and longitudinally through the oven, and

Fig. 11 is an enlarged detail view showing the construction of the hinges for the oven door.

Fig. 12 is an enlarged detail view showing the manner of attaching the legs.

From Fig. 1, it will be seen that in general arrangement the range has a body portion *a* supported on legs *b* and provided with a top plate *c* carrying electrical hot plates *d*. Rising from the rear edge of the body portion is a back *e* and extending from this back and spaced above the top plate is an oven *f*. Alongside of the oven is a shelf *g* which may also be provided with a hot plate *i*.

The construction of the frame work of the range will be most clearly understood by referring to Fig. 2. It will be seen that the frame for the body portion of the range comprises two similar rectangular members 10 and 11, each formed of angle iron, and corner brackets securing these members in spaced relation, the rear corner brackets being designated by the numeral 12 and the front ones by numeral 13. In the present instance, the front sill and the side sills of each of the members 10, 11 are formed of one angle iron, while the rear sill is made separately. The angle between the horizontal and vertical webs of the angle irons forming the top frame member 10 faces inwardly and upwardly, while the angle between the webs of the bottom frame member 11 faces inwardly and downwardly.

The horizontal webs of the members 10 and 11, respectively, are secured by spot welding, rivets or otherwise to the upper and lower ends of the brackets 12 and 13. Each of the front corner brackets 13 may be of angular shape in cross section and provided with flanges 15 at its upper and lower ends to 105 which the horizontal webs of the members 10 and 11 are secured. Extending from the front edges of the brackets 13 are wings 16

which receive the covers for the switches and their fuses as hereinafter described. If desired, braces 17 may be positioned between the corresponding side sills of the members 10 and 11. 18 denotes a strut of angle iron secured at its ends to the front and rear sills of the member 10.

The numeral 20 designates the skeleton frame for the back of the range comprising an angle iron the ends of which receive and are secured to the outside corners of the rear corner brackets 12. The framework which constitutes the corner irons for the oven comprises two members 23 of similar construction and each being formed of an angle iron bent to the shape shown. These members are suitably secured to the member 20. The numeral 24 designates bracket arms secured to the member 20 and supporting the shelf *g*.

From Fig. 12 it will be seen that legs are secured by means of screws 21 to anchor members 22 positioned in the corners of the frame member 11 and secured thereto by bolts 25. It will be noted that the legs may be attached to and detached from the range with great facility as ready access may be had to the screws from beneath the body portion of the range. The flanges of the frame member 11 conceal the anchor members 22.

The manner in which the end panels 26 are assembled on the body portion of the frame is shown clearly in Figs. 2 and 4. It will be seen that the upper and lower edges of the panel 26 are turned inwardly providing flanges 27 and the upper and lower ends of the braces 17 and the brackets 12 and 13 are notched as at 28 to receive these flanges. Thus each panel may be very easily assembled by merely bringing the flanges 27 into registry with the notches 28 and then pushing the panel inwardly, no other means than friction being provided for securing the panel in place.

From Figs. 1, 6 and 7, it will be seen that the oven is supported on brackets 30 and 31 which rise respectively from the cross strut 18 and the right hand side sill of the member 10. These brackets in one manner of speaking constitute portions of the frame work. At the left hand end of the range is a bracket 32 preferably formed of sheet metal and which aids in supporting the shelf *g*. The shelf *g*, together with a panel 33 rising from the back edge thereof, is preferably formed of sheet metal. The edges of the shelf are bent to form a depending skirt 34 and the edges of the panel 33 being bent to form a flange 35 which fits snugly within the portion of the frame member 20 at the left side of the oven. Beneath the shelf *g* and between the brackets 32 and 30 is a sheet metal panel 36 the edges of which are also turned inwardly to provide flanges 36^a. One side

flange of this panel abuts snugly against the bracket 32 and the other engages in a rearwardly facing angle formed by a laterally extending flange 37 on the bracket 30. Beneath the oven and positioned between the brackets 30, 31, is a panel 38 similar to the panel 36. These panels may be inserted from the back of the range and are held in position by studs or pins 39 in the rearwardly extending webs of the brackets 30, 31, and taking into notches 40 in the flanges of the panels, as most clearly shown in Figs. 6 and 7. The top plate *c*, preferably formed of sheet metal, is recessed or slotted at its rear edge to accommodate the brackets 30, 31 and this rear edge is upturned to form a lip 42, as shown in Fig. 6. It will be seen that the lower ends of the panels 36 and 38 extend below the upper edge of the lip 42. If desired, the panels 33, 36 and 38 may be white enamelled.

Positioned at the front of the body portion *a* between the corner brackets 13, 13, are the switches 44 and the fuses 45, the base members 46 of which are suitably secured to the cross bars 47. A sheet metal partition 48 closes the back of the chamber in which the switches are located. It is preferable that the switches and the fuses be enclosed to effect a neat appearance while at the same time access thereto may be readily had. To this end, there are provided removable cover plates 49 and 50 for the switches and fuses, respectively. The plate 49 has a plurality of apertures the edges of which are flanged and fitting over these flanges are caps 49^a through which extend the operating stems of the switches. The ends of the covers 49 and 50 seat on the wings 16. It will be seen from Fig. 3 that the upper edge of the cover 49 is received in a groove provided between the member 10 and the offset edge of the member 48; the lower edge of the plate 50 is received by a groove between the bar 47 and the angle iron member 11; and the adjacent edges of the covers are bent inwardly and abut as at 51. It will be readily seen that to gain access to the switches or fuses, it is merely necessary to pull the cover plates forwardly.

To prevent grease and the like, which may splash onto the top plate, from running down between the hot plates *d* and the edges of the openings in which they are positioned on the top plate *c*, the edge of each of these openings, as most clearly shown in Fig. 9, is bent upwardly to form an upstanding lip 53, and the hot plates have laterally extending, downwardly curved flanges 54 covering these lips.

Reference will now be made to the construction of the oven which is most clearly shown in Figs. 10 and 11. It will be seen that the oven has an outside shell consisting of sheet metal side panels 60 fitting within

the respective corner irons 23; top and bottom panels 61 with their edges turned to form flanges 62 which abut against the side panels, and a rear panel 63 secured in position forwardly of the rear edges of the side panels so as to leave a space behind the oven through which the electric conducting wires may be led. This outer shell is lined with suitable heat insulating material 64 which may be in the form of blocks or slabs. 65 indicates the inner lining or shell of the oven. The top, bottom and side walls of this lining are preferably formed of a single piece of sheet metal bent into hollow rectangular shape. Each of these walls has a concaved portion or depression 65' which serves to space the other portions of the lining from the insulation material 64 thus providing air spaces 67 which aid in heat insulating the inner lining. The depression in the bottom of the lining forms a well or cup which catches the products of condensation, such as water and grease, and thus prevents them from running out of the oven. The heat within the oven tends to vaporize these drippings especially when the unit is immediately above the well, as in Fig. 10. The rear wall 68 of the inner lining is welded to the other walls and is spaced from the insulating material 64. 70 indicates the front frame of the oven which may be secured to the forward ends of the corner irons 23 by bolts 71. It will be seen from Figs. 10 and 11, that surrounding and welded to the forward end of the lining 65 is a throat piece 72, the outer edge of which is bent to form a lip taking into a groove 73 in the front face of the front 70. The inner lining or shell of the oven may be removed as an entirety by merely taking out the bolts 74 and then drawing the lining forwardly through the frame 70. Owing to the fact that the insulation 64 is in the form of slabs or blocks, this insulation will not be disturbed when the lining is removed. Hung on each side of the oven in any suitable manner are racks 75 having suitably spaced cleats for supporting shelves or cooking utensils. 76 denotes a heating unit which is placed in the lower part of the oven, as shown in Fig. 10, when baking is desired. This unit may be positioned on the topmost cleat when the food is to be broiled. 77 denotes terminal plugs adapted to receive the terminal pins of the heating unit. The door of the oven consists of a casting 78 having a panel 79; a lining 80, and heat insulating material 81 interposed between the lining and the panel. The construction of the hinges for the oven door is of advantage in that when the door is closed, the hinged edge of the door will be in close engagement with the opposing face of the front 70. As seen from Fig. 11, 83 denotes a hinge member in the form of a yoke having a stem 84 slidably mounted in a bearing in the front 70, and about this stem and between a collar 85 thereon and the front 70 is a compression spring 86 which urges the hinge member inwardly. The oven door has a lug 87 connected to the hinge member by a pin 88. It will be seen that with this hinge construction, the oven door, (the edge of which is preferably tapered as shown) when it is closed, will extend into and snugly fit in the tapered throat piece 72, thus providing a gas tight closure. The rear of the back 2 and the oven may be covered over by a sheet or plate of metal 90. The angle iron members of the framework are suitably apertured, as at 91, to receive the insulators 92 for the conducting wires 93 leading to the hot plates. It will be noted that all of the conducting wires are concealed from view, those for the hot plate 9 and the oven heating unit 76 being led through the space provided between the rear plate 90 and the panels carried by the back frame. It is, of course, obvious that the invention is susceptible of various modifications and changes which are within the spirit of the invention without departing from the scope of the following claims, it being understood that the present disclosure of the invention is by way of illustration only and it is not to be taken as restrictive of my conception. I claim as my invention:—

1. In a device of the character described, a body frame, a back frame and an oven extending forwardly from the latter, said body frame and back frame being formed, in part, of irons angular in cross section, panels carried by said back frame, a plate covering the rear of said back frame and oven, insulators carried by the angle irons of said frames, and conducting wires passing through said bushings and the space provided between said panels and oven and said plate.
2. In a device of the character described, a plate having an opening provided with an upturned edge constituting an annular lip, and a removable electrical heating unit positioned in said opening and including a casing enclosing a resistance wire, said casing having an outwardly extending flange extending over said lip whereby to prevent grease or the like from passing down between said unit and plate.
3. In a device of the character described, a plate formed of sheet metal and having an opening the edge of which is turned to form an upstanding lip, and an electrical heating unit positioned in said opening and provided with an outwardly extending, downwardly curved flange covering said lip.
4. In a device of the character described, a body portion, a plurality of heating units, switches therefor positioned within the front

of said body portion, a removable cover in front of said switches having a plurality of flanged openings, and a cap closing each flanged opening and having apertures 5 through which the operating stems of the switches extend.

5. In a device of the character described, a body portion having a pair of spaced apart forwardly extending wings, a plurality of heating units, a plurality of switches for said units positioned between said wings, and a removable cover plate for said switches having its ends supported by said wings.

10 6. In a device of the character described, a body portion having top and bottom front sills and a pair of spaced apart forwardly

extending wings, rows of switches and fuses between said sills and wings, grooves provided on said sills, a removable cover for 20 said switches having its upper edge engaged in one of said grooves and its side edges resting on said wings, and a removable cover for said fuses with its lower edge engaging in the other of said grooves and its side edges 25 resting on said wings, said covers having their adjacent edges inturned and abutting.

7. In combination, an electrical hot plate, an oven, means for supporting said hot plate in position at the bottom of said oven 30 and in position at the top of said oven, and contacts carried by said oven for engagement with the terminals of said hot plate.

JOSEPH F. LAMB.
